UNITED STATES PATENT OFFICE

2,428,974

ROTARY DRUM STRATIFIER FOR
MINERALS

Ernest Kreher, Tampa, Fla.

Application November 6, 1942, Serial No. 464,723

6 Claims. (Cl. 209—451)

1

The primary object of the present invention is to provide a novel and efficient system and apparatus for the separation and collection of gold, tin, and other valuable minerals occurring in their free state in alluvial or glacial deposits, in tailing deposits from mining operations, or in quartz after it has been reduced to a size suitable for handling by a centrifugal pump or by a water jet. The apparatus is particularly adapted for the treatment of relatively finely divided material which can be delivered to the sump of the suction pipe of a centrifugal pump by dredges, by hydraulic, or by any other form of mining and conveying.

A further object of the invention is to utilize the varying effects of the pressure of flowing water, of centrifugal force, and of gravitation upon materials of different specific gravities as means to cause the removal of the lighter particles from the heavier ones. This object is accomplished by the provision of an inclined rotating shell or casing, enlarged beyond its inlet to reduce the speed of flow of a stream of water through the shell, and having means by which some of the materials are carried upward to fall through the stream. Ruffles surrounding the stream act as barriers against which the heavier particles engage and fall downward through the space between the webs of the ruffles where there is substantially no longitudinal movement of the water. The ruffles have channels or passages between the outer edges of the webs and the inner surface of the shell to permit the heavier particles to gravitate down the inclined surface to a locked receptacle at the lowermost point of the shell.

The length and shape of the shell will be determined by the material to be treated and by such considerations as cost, weight, ease of transportation and of operation, and power requirements.

The speed of the stream of water will be regulated in accordance with the length of the chamber and its rate of rotation to secure the desired results with the material being treated.

Since the force exerted by flowing water is proportional to the area against which it engages, the same force will cause a greater travel of a particle of small mass than of a particle of equal area but of greater mass, and the effect of gravitation or of centrifugal force will cause a particle of greater mass to overcome the resistance of the water in which it is suspended, more rapidly than a particle of equal area but of smaller mass will overcome the same resistance. Hence the lighter materials will be carried through the separator more rapidly and with fewer contacts with the ruffles than will the heavier metallic particles.

In Patent No. 2,217,687, granted October 15, 60

2

1940, to Ernest Kreher, Karl Kreher and Charles Marr Young, an apparatus for mineral separation is described which has a stationary shell with a plurality of ruffles. It has been found that the spaces between the ruffles fill with matrix in so short a time of operation that the time lost in cleaning and collecting the metal rendered the apparatus relatively inefficient. In the present device, the matrix will not clog the spaces between the ruffles and cleaning is needed only for repairs or replacements.

An important object of a modified form of the apparatus is the provision of means for the discharge of the lighter materials at the upper end of the inclined shell and for the continuous escape of the heaviest particles at the lower end of the shell through an opening of a size chosen in accordance with the quantity of the heavy, valuable materials present in the matrix being treated.

Another object is the provision of a receptacle for gold or other highly valuable metals, which can be locked to prevent theft.

Other objects of the invention will be evident during the consideration of a preferred embodiment selected for purposes of illustration. It will of course be understood that the invention is not limited to the details of construction shown in the accompanying drawings, but many changes in size, form, proportions and structure may be made without departure from the invention as claimed.

In the drawings, Figure 1 is a side elevation of a preferred form of the device including a cylindrical separator, a centrifugal pump, and an electric motor; Fig. 2 is a central longitudinal section on a scale four times as large as that of Fig. 1, showing the construction of the end members of the separator and their connection with the inlet and outlet tubes, the central part of the separator chamber being broken away; Fig. 3 is a plan view of the structures shown in Fig. 1, on the same scale; Fig. 4 is a view, partly in elevation and partly in section, on approximately the plane indicated by the line IV—IV in Fig. 3; Fig. 5 is a transverse section through portions of the separator shell and of the intake end member, looking toward the right in Fig. 2 in the planes indicated by the line V—V; Fig. 6 is an end elevation of one of the ruffles used in the separator shell; Fig. 7 is a diametral section of the same riffle looking toward the right in the plane indicated by the line VII—VII of Fig. 6; Fig. 8 is a fragmentary view looking upward from the bottom of either Fig. 6 or Fig. 7; Fig. 9 is a fragmentary elevation with parts broken away, of the operating lever, the brake drum flange, the stop pawl, and the adjustable end member of the brake band; Fig. 10 is a side elevation of the operating lever and the stop pawl; Fig. 11 is

a section through the spring-pressed collar which holds the discharge pipe in its seat; Fig. 12 is a side elevation with parts in section of the shifter yoke of the friction clutch; Fig. 13 is a fragmentary longitudinal section of a modification of the structure shown in Fig. 2; Fig. 14 is a cross-section through the volute-shaped channel of Fig. 13; and Fig. 15 is a plan view of the metal-collecting receptacle of Fig. 14.

The central portion of the shell or casing of the separator is shown as a cylinder 1 having secured upon its ends flanged members 2 and 3. To the member 2 is secured the flange 4 formed at one end of the intake member 5 which tapers down toward the inlet to a cylindrical bearing portion 6 within which is fitted the discharge end of the intake pipe 7, around which the portion 6 rotates within a bearing member 8. A suitable packing 9 around the pipe is compressed in a stuffing box by the gland 10 and the gland nut 11 held in place by the lock nut 12. The intake pipe 7 may extend into the member 5 to any desired distance since the end of the pipe will not interfere with the flow of material into the separator chamber. To the member 3 is secured the flange 13 of the outlet end member 14 which tapers to a cylindrical bearing portion 15 mounted within a bearing member 16.

At the discharge end of the separator, the interior of the outer end of the outlet member 14 is made flush with the interior of the inner end of the discharge pipe 17 which has a rotating bearing in the socket 18 formed within the portion 15. A collar 19, best seen in Fig. 11, is secured to the pipe 17, preferably by one or more set screws 20. Within this collar are a plurality of sockets 21 for helical springs 22 which bear at their outer ends against a flange 23 of a member 24 secured upon a support 25. A stud 26 secured in the collar 19 projects outward for slideable engagement within a slot 27 formed within the rear edge of the member 24. The stud prevents rotation of the collar 19 and thus of the pipe 17, while permitting the pipe to be held within the rotating socket 18 by the thrust of the springs 22.

A liquid-tight joint between the pipe 17 and the member 14 is provided by a packing 9 in a stuffing box having a gland 10, nut 11, and locking nut 12 such as are used with the pipe 7.

Within the shell 1, throughout substantially its entire length, are a plurality of rifles 28 each consisting of a flat, annular web mounted radially of the axis of rotation of the shell. From each web project a plurality of vanes 29 each having one wing 30 set more or less radially of the web and at right angles thereto and having a second wing 31 set substantially at right angles to the web and to the wing 30. The wings 31 extend across the outer edge of the annulus 28 to space it an eighth of an inch, more or less, from the interior surface of the cylindrical casing 1 as best seen in Figs. 5, 6, and 14. Six such vanes are shown in these figures, but obviously the number used is a matter of choice or convenience. On the outer end of one of the vanes on each rifle, a V-shaped point 32 will be formed to enter a corresponding recess 33 either in the next adjacent rifle plate toward the inlet or in one of the projections 34 formed on the inner periphery of the member 2 against which the outer ends of the end vanes of the series abut when the assembly of rifles is installed within the cylinder 1. A plurality of screws 35 extending through the flange 13 are arranged to bear against the side

of the outermost rifle to clamp the whole group of rifles together and force the lowermost rifle against the projections 34, thus preventing the group from turning within the cylindrical shell.

5 Except for the projecting lugs 34, the interior of the member 2 is substantially flush with the inner surface of the cylindrical shell 1, so that material sliding downward beneath the lowermost rifle web between the wings 31 may pass freely through the spaces between the lugs 34 into the tapered end member 5.

Formed upon or secured to the central portion of the end member 5 is a brake drum 36 upon a side face of which is secured a bevel gear 37 in 15 mesh with a smaller bevel gear 38 on a shaft 39. A pulley 40, driven by a belt 41 from an electric motor 42 and running freely on the shaft 39 may be connected to the shaft to cause rotation of the gears by the use of any suitable clutch, such 20 as the expanding ring type of friction clutch shown at 43 in Fig. 3. The shifter yoke 44 for the clutch shown in Figs. 3 and 12 as carried by a sliding plate 45 operated by a push rod 46 is caused to move into and out of operative position 25 by a lever 47 to which the rod 46 is pivoted at the lowermost end of the lever. The lever 47 is pivoted on a support 48 closely adjacent to a flange 49 on the brake drum 36. The plate 45 may also carry a link 45' to operate a switch 42' 30 controlling the motor 42.

The lever 47 is provided on the edge adjacent to the brake drum with a lug 50 engaged on opposite faces by the wings of a nut 51. This nut is adjustable longitudinally of the threaded end 35 of a rod 52 pivoted at 53 on one end of the brake band 54. After adjustment of the nut, it is secured upon the lug by a pivot 55.

The other end of the brake band is secured by links 56 to the member 48. A stop pawl 57 is 40 pivoted beside the lever 47 on the member 48 with the pawl lying in the plane of the flange 49. A notch 58 is cut in the periphery of the flange and provided with a cushion, which may be formed of leather strips 59 glued together and 45 bolted upon the flange at the end of the notch for engagement with the end of the pawl 57. A bolt 60 has a terminal yoke 61 pivoted at 62 on the pawl, the shank of the bolt being surrounded by a helical spring 63. A lug 64 projects laterally 50 from the rear edge of the lever 47 and has a perforation through which the bolt 60 passes. A nut 65 on the opposite face of the lug from the spring holds the bolt and the pawl in place with the ends of the spring engaging the yoke 61 55 and the lug 64.

As the lever 47 is pushed forward from the broken line inoperative position of Fig. 9 toward the brake drum, it acts to perform several operations in sequence: first, it pulls on the rod 46 to 60 cause the plate 45 to slide to open the switch 42' of the motor and to move the shifter yoke 44 to disengage the clutch 43. The separator through its inertia will continue to revolve for awhile after the clutch is released and the operator at the proper time will move the lever farther forward to cause a downward pull on the nut 51 to tighten the brake band and thus to slow down the rotation of the shell. Forward movement of the lever will bring the pawl into contact with the rim 70 of the flange 49 but it can be withdrawn if the speed is too great. As the notch 58 is seen approaching the pawl, the lever can be moved forward strongly to complete the action of the brake band just as the pawl engages the end of the 75 notch, this being the position in which the recep-

tacle 67 or 68 is at the lowermost point of the separator assembly. The spring 63 is compressed as the lever moves to its extreme forward position without corresponding movement of the pawl.

This sequence of operations releases the separator from the driving force of the motor, applies a gradually increasing friction on the brake drum, and finally stops the shell at a definite point, which is the position shown in Figs. 1 to 5, 13 and 14.

The motor 42 is connected by belts 69 with the drive shaft 10 of a centrifugal pump 71 having an intake pipe indicated at 72 and a discharge nozzle at 73. The intake pipe 72 is of a length to connect the pump with a sump or tank provided to receive the matrix to be treated and to receive material discharged from the shell when it has been stopped, as for the removal and replacement of a receptacle.

As seen in Figs. 1 and 3, the discharge nozzle 73 is connected with the pipe 7 by a flexible hose 74 of any suitable length. While it is shown in these figures as short, it will be evident that the hose serves merely as the necessary connection between the pump or water jet at the sump and the separator which may be at a considerable distance away for greater convenience in use.

The material to be treated by the present separator will be of sizes no greater than can pass readily through the intake pipe 72, larger pieces being removed by screens or other apparatus, not shown, to obviate any danger of clogging any of the passages in the apparatus.

The stream of water carrying the mixture of minerals in suspension will be driven through the pipe 7 into the upwardly inclined rotating separator whose shell has a diameter greater than that of the pipe. The velocity of the stream of water will be reduced because of this larger diameter of the shell, while the riffles will prevent a free flow of the water along the outer portion of the chamber. The greatest velocity will be maintained substantially along the axis of rotation.

The material will consist of particles differing in specific gravity. With equal pressure of the flowing water, the lighter portions will be carried faster and farther than the heavier ones, but the speed of flow will be so regulated that the heavier materials to be retained will drop down at the reduced speed of flow within the intake member 5 or between the webs 28 of the riffles where there is substantially no forward movement of the water.

The centrifugal force caused by the rotation of the shell will exert a greater outward pressure of the heavier particles than of the lighter ones, toward the wall of the casing. The lighter particles suspended in the central rapid current will be very little affected by the centrifugal force.

In locations where clay or the like causes the matrix to adhere in lumps, one or more breaker bars 76 may be secured to the wings 30 of the riffles as indicated in Fig. 6, to extend across the middle of the stream to be engaged by the lumps to cause them to disintegrate. Material between the webs of the riffles encountering the wings 30 will be carried upward and dropped again into the top of the flowing stream. The repeated tumbling over of the matrix assists in washing and scouring from the metallic particles films or encrustations of lighter materials by the attrition of the individual bits or pieces against each other and against the apparatus.

The lighter portions will travel upward and outward at a rate substantially in proportion to their weight after deducting the weight of the water they displace. The heaviest particles falling and being thrown by centrifugal force against the interior surface of the shell will slide downward along the inclined surface, passing through the spaces between the wings 34 and between the outer edges of the riffle webs and the inner surface of the shell.

A steady and free flow of the materials may be assisted by the percussive impacts of electro-magnetic vibrators indicated at 75 in Figs. 1 and 13. The angle of inclination can be reduced if the metallic casing is vibrated to eliminate friction between the material and the surface along which it must travel. With such vibrators in use, the possibility of clogging of the spaces between the webs of the riffles is materially reduced.

The heaviest particles, sliding downward along the inclined inner surface of the shell, will finally reach the lowermost end and will enter the widest portion of the member 5. In Figs. 2 and 13, the interior of the member 5 is shown as expanding or widening toward the left from the flange 4 to a channel 66 which may be formed as a volute in section, as best seen in Fig. 14, with the receptacle 67 at the greatest distance of the curve from the axis of rotation, or the channel may be substantially concentric with the axis as shown in Figs. 2 and 5, with the receptacle 68 at the end of a lateral pocket.

In Fig. 2, the member 5 is shown as provided on its interior with a protector ring 76 which may consist of one or more pieces secured to the member 5 by screws 77. This ring extends forward beyond the channel 66 to direct the stream of water into the cylindrical shell 1 to prevent the stream from directly entering the channel to wash out material that has gravitated into it, while if any such material should be carried upward and fall from the receptacle, it would engage the outer surface of the ring and thus be prevented from falling into the stream.

The structure shown in Fig. 13 omits the protector ring, since, with the volute channel, the centrifugal force of rotation at a proper speed will be sufficient to hold the heavy metal in the receptacle.

In both Fig. 2 and Fig. 13, a padlock 78 is shown in a stud 79 secured in the member 5 to prevent sidewise outward movement of the receptacle 67 or 68 each of which has an ear 80 to receive the stud as the receptacle is slid into position between the lugs 81 and 82. The front edge of the rim of the receptacle is beveled at 83 to engage within a correspondingly undercut notch in the member 5. The lug 81 has a beveled upper surface to be engaged by the tapering smaller end of the receptacle while the lug 82 has a set screw 84 to thrust the receptacle longitudinally and upward to bring the smoothly ground upper surface into liquid-tight contact with the smooth lower surface surrounding the outlet of the channel 66. Even with the screw 84 released, the receptacle cannot be pried downward because of the beveling at 83 and with the lock 78 preventing lateral movement.

Such closed and locked receptacles which can be opened only by persons having a key will effectively prevent theft where such precaution is necessary or desirable, but in many cases a continuous discharge of the heavy metals entering the receptacle may be preferred. In Fig. 2, the receptacle designated as 85 is provided with an

opening 86 at the outermost point radially from the axis of rotation for the continuous escape of water and for the escape of any minerals that may gravitate to this outlet. A metallic hood 87 surrounds the shell 1 at its lower end and the end member 5 near the channel 66 to receive the concentrate discharged from the opening 86. Receptacles will be provided having openings of different sizes from which to select the proper outlet to agree with the rate of concentration, which will be dependent upon the relative quality of metal in the matrix, on the proportion of solids to water in the flowing stream, on the speed of the stream, and on other factors.

The apparatus will thus provide a continuously operating separator from which the lighter materials will be discharged at the upper end and the heavier materials at the lower end. While some of the lighter minerals may accompany the heavier minerals to the receptacle, there is no force acting on the heavier minerals that can discharge them at the upper end once they have dropped from the flowing stream, unless they are embedded in or attached to lighter bodies of which they form a minor portion.

Lugs 88 shown in Fig. 14 serve as a pedestal to support the receptacle when it is removed and set down on a flat surface and also provide a place to be struck with a hammer to dislodge the receptacle when taking it off the shell.

It will be understood that the details of construction shown and described are purely illustrative and the invention is to be construed broadly within the full scope and meaning of the claims.

I claim:

1. A separator for minerals differing in specific gravities comprising a separator chamber having an inlet member, a central portion of greater diameter than that of the inlet member, and an outlet member, the inlet and outlet members being mounted for rotation in bearings of which the bearing for the outlet member is the higher, a plurality of annular riffles having their outer edges separated from the inner surface of the central portion and their inner edges surrounding the central opening substantially concentric with the axis of rotation of the chamber, means for forcing a stream of water having finely divided minerals in suspension therein through the inlet member into the separator chamber, means for rotating the separator chamber, and means carried by a rotating member to engage material between the riffles and to carry it upward to the upper portion of the flowing stream.

2. A separator for a mixture of finely divided minerals differing in specific gravities which comprises means providing an inlet passageway for a stream of water carrying the mixture in suspension, an upwardly inclined shell of larger internal diameter than that of the inlet, whereby to cause the speed of flow of the stream to be lessened, a plurality of annular riffles having webs extending transversely of the shell and having portions of their outer edges spaced from the interior of the shell, the webs having wings extending into the spaces between the webs, and means for rotating the riffles around the stream, whereby material engaged by the wings will be moved sidewise from below the stream, upward at one side of the stream, and discharged into the stream, and whereby heavier particles may slide downward within the inclined shell.

3. A mineral separator comprising a rotating shell having an end member at its lower end,

means within the shell permitting gravitation of heavy minerals down the inner surface of the shell, the end member being provided with a channel to receive material from the shell, the bottom of the channel gradually increasing in radial distance from the axis of rotation of the shell, and a receptacle at the point of greatest distance of the bottom of the channel from the axis.

- 10 4. A structure as in claim 3 in which the receptacle is provided with an opening for the escape of material entering the receptacle, and in which there is a hood surrounding the locus of travel of the receptacle to receive material leaving the opening.
- 15 5. A separator for minerals comprising a tubular conveyor for flowing water, including an intake portion and an inclined rotary separator chamber, a plurality of annular riffles mounted within the chamber transversely of its axis of rotation and having portions of their exterior peripheries separated from the inner wall of the chamber, each riffle having a central aperture substantially concentric with the axis of rotation of the chamber and of greater area than that of the intake portion whereby to reduce the rate of flow of water through the chamber, means for rotating the chamber, and means for forcing water carrying minerals of different specific gravities in suspension upward through the tubular conveyor, the arrangement being such that heavier particles of the suspended materials at the slower rate of flow within the chamber will engage the baffles to arrest forward movement.
- 20 6. A mineral separator comprising a substantially cylindrical shell having an annular end member secured upon the lower end thereof, a plurality of riffles having projecting portions engaging the inner surface of the shell to space the outer edges of the riffles from the shell to provide passageways between the riffles and the shell, the riffles being slidably longitudinally of the shell for assembly in spaced relation with their webs radial to the shell, the said end member having lugs projecting inward for engagement with the lowermost riffle of the assembly and having the inner edge of the annular member substantially flush with the inner surface of the shell in spaces between the lugs, and
- 25 means for clamping the riffles removably within the shell for rotation therewith.
